W. G. BEATTY

WRINGER

Filed Nov. 30, 1926

INVENTOR:

William G. Beatty
James H. Hough

UNITED STATES PATENT OFFICE.

WILLIAM GEORGE BEATTY, OF FERGUS, ONTARIO, CANADA.

WRINGER.

Application filed November 30, 1926. Serial No. 151,807.

According to my invention the wringer, which comprises a set of rolls and a hinged cover, is provided with a spring for exerting pressure on the rolls, and means for maintaining the spring in, or for instantaneously releasing it from, pressure exerting relation with the rolls.

In the preferred embodiment of the invention the cover is constructed interiorly with supporting members above and parallel with the journals of the rolls, and a flat spring is placed within the cover and its ends are loosely mounted on the supporting members. Pressure blocks are seated on the journals of the uppermost roll and extend above the supporting members to be engaged by the spring. A rotatably adjustable cam or disc is mounted in the cover and engages the spring for varying the pressure exerted by it on the rolls, and a crank or the like effects the rotatable adjustment of the cam or disc.

The cover is exteriorly provided with locking members which may take the form of lateral projections, and a reciprocatingly movable locking bar is slidably connected to the wringer frame and is provided with locking members which may take the form of elongated hooks for engaging the locking members of the cover. A lever is fulcrumed to the wringer frame for actuating the locking bar and the movement of this lever in one direction brings the locking members into engagement for securing the cover and the movement of the lever in the opposite direction actuates the locking bar for the instantaneous release of the locking members.

For an understanding of the invention reference is to be had to the following description and to the accompanying drawings, in which:

Fig. 1 is a plan view of a wringer constructed according to this invention,

Fig. 2 is a front elevation of the same showing in full lines the locking means actuated to secure the cover for maintaining the spring in pressure exerting relation with the rolls and showing in dotted lines the locking means actuated to release the cover for relieving the pressure, and

Fig. 3 is a sectional elevation of the construction shown in Fig. 2.

Like characters of reference refer to like

parts throughout the specification and drawings.

Journalled in the main frame 25 are two wringer rolls 31 31^a and bearing on the journals of the roll 31 are pressure, or journal, blocks 32. Hinged to the top of the main frame 25 is the cover 33 provided with a downturned flange 34, and extending through the flange 34 are two supporting members 35, the axles of which are parallel with the journals of the roll 31. Within the cover 33 is a leaf spring 36 for exerting pressure on the blocks 32, and, the ends of this spring loosely rest on the supporting members 35 when the cover part is released by the locking bar 40 hereinafter described. Centrally journaled in the top of the cover is the axle 37 of a rotatable cam or eccentrically mounted disc 38, and fitted on the end of the axle, beyond the cover 33, is a crank 39. The disc continuously engages the spring 36 and when rotated varies the tension of the spring. The pressure blocks 32 extend above the supporting members 35 when the cover is in a closed position and lift the ends of the spring from the supporting members so that when the cover is closed and secured in its closed position, the spring will be at all times in pressure exerting relation with the blocks and by means of the latter with the wringer roll 31. When the disc 38 is rotated to the position shown in dotted lines in Fig. 3, the spring 36 is tensioned to the minimum degree and when the disc is turned to the position shown in full lines in Fig. 3, the spring is tensioned to the maximum degree.

This construction provides a simple and rapid adjustment for correctly varying the pressure on the rolls.

The disc 38 is rotated slightly beyond its central position for applying the maximum pressure of the spring, and the crank 39 is then in the position shown in full lines in Fig. 3 and engages the cover 33. The disc is prevented from inadvertently moving from this position in one direction by the engagement of the crank 39 with the cover, and is prevented from inadvertently moving in the other direction by its engaging relation with the spring and by the weight of the crank.

Other types of springs and tension devices

may be employed in lieu of the specific type shown and described and it is not intended that the invention should be limited to this specific construction.

5 The cover, including the pressure exerting means, are for convenience, termed the cover part, and for holding the cover part in operative relation with the wringer rolls, a locking bar 40 is reciprocatingly attached to the main frame 25. This locking bar is formed with elongated slots 41 through which are entered headed bolts or studs 42 projecting from the main frame 25, for slidably securing the locking bar to it and for guiding the locking bar during its reciprocating movement. The locking bar is provided with two hooks 43 spaced to come into engagement with two projections 44 on the cover 33, and by their engagement with the projections, securely lock the cover in its closed position and maintain the spring in pressure exerting relation with the rolls. The hooks on the locking bar are comparatively long and so shaped that they draw the hinged cover down to its locked position and impose the pressure of the spring on the pressure blocks 32.

At the bottom of each hook 43 is a slight recess into which the projections 44 drop when the locking bar is moved to the limit of its locking position, for preventing the inadvertent displacement of the hooks from the projections 44. Extending horizontally from the locking bar is a lug 45 formed with a slot 46 through which is entered a wringer release lever 47, the lower end of which is fulcrumed at 48 to the main frame 25. The actuation of the lever 47, operating through the slot 46, effects the movement of the locking bar in one direction for the engagement of the hooks 43 with the projections 44 and in the opposite direction for the release of the hooks from them. The release of the locking bar from the projections immediately releases the cover part and relieves the pressure of the spring on the blocks 32 and wringer roll 31, the ends of the spring then resting on the supporting members 35.

Having thus fully described my invention what I claim as new and desire to secure by Letters Patent is:

55 1. A wringer comprising a wringer frame, a set of rolls therein, a hinged cover for the rolls, a spring within the cover for exerting pressure on the rolls, a rotatable eccentric disc engaging the spring for varying the pressure exerted by it on the rolls, and a reciprocatingly movable locking bar having a slidable connection with the wringer frame for securing the cover and maintaining the spring in pressure exerting relation with the rolls.

60 2. A wringer comprising a wringer frame, a set of rolls therein, a hinged cover for the rolls, a spring within the cover for exerting

70 pressure on the rolls, a rotatable eccentric disc engaging the spring for varying the pressure exerted by it on the rolls, and a reciprocatingly movable locking bar having a slidable connection with the wringer frame for securing the cover and maintaining the spring in pressure exerting relation with the rolls, the cover having projections and the locking bar having hook-shaped members for engaging the projections.

75 3. A wringer comprising a wringer frame, a set of rolls therein, a hinged cover for the rolls, a spring within the cover for exerting pressure on the rolls, a rotatable eccentric disc engaging the spring for varying the pressure exerted by it, a reciprocatingly movable locking bar having a slidable connection with the wringer frame for securing the cover and maintaining the spring in pressure exerting relation with the rolls, and a lever actuating the locking bar, the cover having projections, and the locking bar having hook-shaped members engaging the projections.

80 4. A wringer comprising a wringer frame, a set of rolls therein, a hinged cover part having means for exerting pressure on the rolls, projections extending laterally from the cover part, and a reciprocatingly movable locking bar having a slidable connection with the wringer frame engaging the projections for securing the cover part and the pressure exerting means in operative relation with the rolls or disengaging the projections for releasing the cover part and relieving the pressure exerted on the rolls.

85 5. A wringer comprising a wringer frame, a set of rolls therein, a hinged cover for the rolls, means for releasably locking the cover in a closed position, a leaf spring within the cover for exerting pressure on the rolls, pressure blocks interposed between the spring and the rolls, means within the cover on which the ends of the spring are loosely supported when the cover is released, and means engaging the spring for varying the pressure exerted by it.

90 6. A wringer comprising a wringer frame, two rolls therein, pressure blocks for the journals of one of the rolls, a cover for the wringer, means for releasably locking the cover in a closed position, a spring within the cover engaging the pressure blocks for exerting pressure on the rolls, supporting means within the cover on which the ends of the spring rest when the cover is released, said means being below the top of the blocks and free from contact with them, and means for varying the pressure exerted by the spring.

95 7. A wringer comprising a wringer frame, two rolls therein, pressure blocks for the journals of one of the rolls, a cover for the wringer, means for releasably locking the cover in a closed position, a spring within the cover engaging the pressure blocks for exert-

ing pressure on the rolls, supporting means within the cover on which the ends of the spring rest when the cover is released, said means being below the top of the blocks and 5 free from contact with them, means for varying the pressure exerted by the spring, projections extending from the cover, and a locking bar slidably connected with the frame and having hook-shaped members for

engaging the projections and securing the 10 cover and maintaining the spring in pressure exerting relation with the rolls.

Dated at the town of Fergus, in the county of Wellington, and Province of Ontario, Dominion of Canada, the 30th day of October, 15 1926.

WILLIAM GEORGE BEATTY.
